EXTRUDED COPING STRIP FOR SWIMMING POOLS

Joe H. Lamb, Salt Lake City, Utah, assignor to Philip A.
Mallinckrodt, Salt Lake City, Utah

Filed Sept. 30, 1960, Ser. No. 62,320

Term of patent 14 years

(Cl. D13—6)

FIG. 1.

FIG. 2.

FIG. 1 is a perspective view showing one end, the top, and the front of an extruded coping strip for swimming pools embodying my new design;

FIG. 2 is a perspective view showing an end, the bottom, and the rear of such strip.

I claim:

The ornamental design for an extruded coping strip for swimming pools, substantially as shown.
